UNITED STATES PATENT OFFICE

FRED BERGMANN, OF PHILADELPHIA, PENNSYLVANIA

SANITARY CAP REMOVER

Application filed April 10, 1930. Serial No. 443,175.

This invention relates to a sanitary cap remover particularly adapted for the removal of the paper or cardboard caps ordinarily used on milk bottles.

The removal of these paper closure members or caps ordinarily used on milk bottles and similar types of containers is sometimes quite difficult. The paper caps are usually forced under an overhanging lip on the bottle or container to retain the caps in position. They are also usually bowed slightly inwardly toward the contents of the bottle. This renders their removal most troublesome. If an attempt is made to force the paper cap inwardly toward the bottle, pressure is put upon the liquid in the bottle and the liquid quite frequently splatters outwardly. It is a common practice for housewives to puncture the paper caps with a fork, ice pick, or similar pointed implement in an attempt to remove the same. However, this operation must be most carefully done or otherwise the liquid will be forced out of the bottle.

Some dairies now use a special cap which is readily removable, having a wire for pulling the same out of the bottle, or a tab which may be bent upwardly to pull the cap out. These types of caps are expensive to manufacture and are troublesome to insert since they must be positioned with the wire or tab facing outwardly. Moreover, it frequently happens that the tabs or wires become detached from the caps when an attempt is made to remove the caps.

If the paper caps are removed from the bottles by puncturing them with a fork or similar implement they have a hole through them and if the user wishes to retain some of the milk within the bottle for future use, the perforated cap may be replaced in position but the entrance of dust or other foreign matter into the bottle is not entirely prevented. Where the milk is stored in a refrigerator or similar container in which various other food products are stored, it is desirable that the milk receptacle be closed, or otherwise the unused portion of the milk may become contaminated from odors emanating from the other food products.

It is an object of this invention to provide

a remover for the paper caps of milk bottles or the like, which is readily associated with the bottle to remove the cap therefrom and which prevents all danger of splashing the liquid outwardly upon the user.

Another object of this invention is to provide a remover for the paper caps of milk bottles or the like, which remover may be detachably associated with the milk bottle after the cap has been removed to provide a temporary closure for the bottle which will prevent the entrance of dust into the bottle and maintain it sufficiently air-tight to prevent circulation of air therein.

Another object of this invention is to provide a removing implement for the paper caps of milk bottles or the like, which is in the form of a cup for enclosing the entire end of the milk bottle, with a readily movable part thereon for puncturing the cap, whereby danger of splashing the liquid contents of the bottle on the user is obviated.

Another object of this invention is to provide a remover for the paper caps of milk bottles or the like which is provided with a movable handle having a hook thereon for piercing the paper cap to remove the same, and is further provided with spring means, whereby the paper cap may be readily disassociated from the removing implement after the same has been removed from the bottle.

Another object of this invention is to provide a cap remover for use with milk bottles or the like, which is simple and cheap to manufacture, durable in use, and thoroughly reliable in its operation, said remover performing the double function of providing a remover for the cap and providing a temporary closure for the open end of a milk bottle and the like.

These and various other objects of my invention will be apparent from the following description and appended claims, when taken in connection with the accompanying drawings, wherein—

Figure 1 is a sectional view taken on line 1—1 of Figure 2.

Figure 2 is a side elevation with the casting in section,

Figure 3 is a section on line 3—3 of Figure 100

1 showing the remover positioned on a milk bottle.

Figures 4 and 5 are detailed views of my spring device for ejecting the paper cap from the remover.

Referring to the drawings, by reference characters, I have provided a cup-shaped casing 1 having a closed bottom 2 with the depending wall 3 thereon, said member being preferably formed from sheet metal such as aluminum or the like and being of a size to readily fit over the neck of a milk bottle or other container from which the cap is to be removed. The depending wall 3 is perforated adjacent the junction of said wall with the closed bottom 2 for the reception of a rotatable shaft 4 journalled in the wall 3 and having retaining washers 5 thereon for maintaining the handle in position. This shaft is provided with an external manually operable crank 6 for operating the same. The shaft 4 has secured thereto for rotation therewith a pointed hook member 7 which is adapted to perforate through the paper cap to remove the same. As seen in Figure 3, the hook member 7 may be retracted within the cup-shaped member 1 to a position spaced from the bottom edge provided by the cup-shaped wall 3. The hook 7 may be secured to the shaft 4 in any approved manner, such as a clamped fit around a squared portion of the shaft, or otherwise, in order that the shaft 4 and the hook 7 may rotate as a unit.

In order to provide for the detachment or ejection of the paper cap from the cup-shaped casing 1, I have provided a spring device which automatically disconnects the paper cap from the casing when the handle is turned in a reverse direction.

This spring device includes a flat metal spring member 8, shown in detail in Figures 4 and 5. This spring member is formed by bending a flat sheet metal strip upon itself to form the two leaves 11 and 12. The upper leaf 11 of the spring 8 has two tongues 13 and 14, cut from the main portion thereof and bent around the shaft 4 into close engagement therewith. The remaining outer portion of the upper leaf 11 thus constitutes a single central leaf designated by reference character 15 and said member 15 rests in surface contact with the closed bottom 2 of the sheet metal casing 1. The lower leaf 12 of the spring member 8 extends across the central portion of the cup 1 and is provided with a central slot 16 adjacent its end to thus provide an opening through which the hook member 7 may pass.

By the above construction it will be noted that the assembly of the parts is greatly simplified, there being no soldering or riveting operations necessary. The spring member 8 is cut and bent into proper form prior to assembly, the tongues 13 and 14 projecting downwardly from the upper leaf 11. The

sole means of support for the spring member 8 comprises the shaft 4. The tongues 13 and 14 and the hook 7 may be bent around the shaft 4 after the shaft has been passed through the opening in one side of the cup 1. The shaft may then be passed through the opening in the side of the casing and the washers 5 secured in position. The washers 5 when secured to the shaft 4 will prevent misplacement of the parts. The entire mechanism is cheap to manufacture and thoroughly efficient in its use.

It is believed that the operation of my device will be obvious from the above description. The cup-shaped member 1 is positioned over a bottle 18 or the like, as shown in Figure 3, pressure on the cup-shaped member 1 slightly compressing the lower leaf 12 of the spring which rests against the paper cap 17 of the bottle 18. When the handle 6 is turned to rotate the shaft 4, the hook member 7 passes through the slot 16 of the spring to perforate through the cap 17. When the cup 1 is now removed from the bottle 18 the paper cap 17 is retained by the hook 7. The paper cap 17 may now be ejected from the remover by a reverse rotation of the handle 6, this reverse rotation withdrawing the hook 7 through the slot 16 of the spring. When such withdrawal takes place the lower leaf 12 of the spring is further compressed and when the pointed end of the hook 7 is withdrawn from the opening in the cap 17, the cap is forcibly ejected by the spring out of the cup-shaped member 1.

The cup 1 may be used as a cover for the milk bottle to prevent entrance of foreign matter until all of the milk is used. When thus used as a cover for a milk bottle the lower leaf 12 of the spring projects slightly downwardly into the bottle and the depending wall 3 extends well below the neck of the bottle. Although I have not shown a close fit between the neck of the bottle and the wall 3 nevertheless the entrance of foreign matter into the bottle is effectively prevented and there is practically no circulation of air in the bottle. It will be understood that in some cases I may make the diameter of the casing such that the walls 3 will frictionally engage the neck of a milk bottle, whereby a practically air-tight seal will be obtained.

If desired, the cap 17 may be retained within the cup 1 and be repeatedly put on and taken off from the bottle. If this operation is desired, the handle 6 is not rotated in a reverse direction to eject the cap 12 but remains in the position to which it was turned when the cap was punctured by the hook 7. Thus the cap 17 may be accurately positioned back onto the bottle and the cup member 1 may remain associated therewith to function as a handle or it may be removed for use with another bottle.

The invention may be embodied in other

specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

10 What I claim and desire to secure by United States Letters Patent is:—

15 1. A device for the removal of the paper cap of a milk bottle comprising a cup-shaped casing adapted to be positioned over the end of the bottle, a rotatable handle member journaled in the depending wall of said casing, a hook secured to and rotatable with said handle member adapted to puncture through and retain the paper cap when said handle member is rotated in one direction and a leaf spring bent upon itself, one portion of said leaf spring being bent around said handle member within the casing for retaining the 25 leaf spring in position, the other end of said spring being slotted for the passage of said hook therethrough whereby the paper cap is ejected from said casing after removal from the bottle by reverse rotation of said handle member.

20 2. The invention as defined in claim 1 wherein the upper rebent portion of said leaf spring is in surface engagement with the closed bottom of said casing.

25 35 In testimony whereof I affix my signature.
FRED BERGMANN.
